FOREIGN PATENT DOCUMENTS

GB 6148346 * 7/2021

Primary Examiner — W. A. Teddy Falloway
Assistant Examiner — Amanda Kay Birdwell(57) **CLAIM**

The ornamental design for a bottle for nail glue, as shown and described.

DESCRIPTION

FIG. 1 is a perspective view of a bottle for nail glue design showing my new design.

FIG. 2 is a front view of a bottle for nail glue.

FIG. 3 is a rear view of a bottle for nail glue.

FIG. 4 is a left side view of a bottle for nail glue.

FIG. 5 is a right side view of a bottle for nail glue.

FIG. 6 is a top view of a bottle for nail glue; and,

FIG. 7 is a bottom view of a bottle for nail glue.

The broken lines in the drawings depict portions of the bottle for nail glue that form no part of the claimed design.

1 Claim, 7 Drawing Sheets(56)
